UNITED STATES PATENT OFFICE.

HOWARD C. NOBLE, OF NEW BRITAIN, CONNECTICUT.

DESIGN FOR A BUCKLE.

SPECIFICATION forming part of Design No. 28,505, dated April 26, 1898.

Application filed February 24, 1898. Serial No. 671,538. Term of patent 7 years.

To all whom it may concern:

Be it known that I, HOWARD C. NOBLE, a citizen of the United States, residing at New Britain, Hartford county, and State of Connecticut, have invented certain new and useful Improvements in Buckles, of which the following is a full, clear, and exact description.

My invention relates to a new and original design for buckles, and the same is illustrated by the accompanying drawings, in which—

Figure 1 is a perspective view of a buckle embodying my new and original design. Fig. 2 is a plan view of the same.

Referring to the drawings, the buckle when viewed in plan is in general of a rectangular outline.

The characteristic or leading feature of this design comprises the peculiar formation at the rear end of the buckle, in which there appear two rearwardly-directed tailpieces at the opposite ends of the U-shaped side bar A,

(which is the connecting-bar near the rear of the buckle, upon which a central tongue is disposed.) These tailpieces, while short, are of sufficient size to be readily visible, as will appear by reference to either of the views in the accompanying drawings.

Another feature is the location of the before-mentioned tongue-bar, which is slightly in advance of the rear ends of the tailpieces and is dropped, so as not to appear to be centrally located with respect to the inner walls thereof.

What I claim is—

The design for a buckle herein shown and described.

Signed at New Britain this 19th day of February, 1898.

HOWARD C. NOBLE.
